UNITED STATES PATENT OFFICE

168,878

TOY WATER PISTOL

Charles Arliss, New York, N. Y.

Application November 7, 1952, Serial No. 22,188

Term of patent 7 years

(Cl. D34—15)

To all whom it may concern:

Be it known that I, Charles Arliss, a citizen of the United States of America and a resident of the city of New York, in the county of Queens and State of New York, have invented a new, original, and ornamental Design for a Toy Water Pistol, of which the following is a specification, reference being had to the accompanying drawing, forming a part thereof.

Fig. 1 is a side elevational view of a toy water pistol, showing my design,
Fig. 2 is a top plan view thereof,
Fig. 3 is a front elevational view thereof, and
Fig. 4 is a rear elevational view thereof.

I claim:

The ornamental design for a toy water pistol, substantially as shown.

CHARLES ARLISS.
